(57) **CLAIM**

I claim the ornamental design for the compact disk carrying case with side webbing, as shown and described.

DESCRIPTION

FIG. 1 is a top view of a disk carrying case with side webbing, showing my new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a bottom plan view thereof.

The broken lines shown throughout the views are understood to represent stitching.
